UNITED STATES PATENT OFFICE.

ARTHUR YANCEY, OF DERMOTT, ARKANSAS.

SEINING APPARATUS.

No. 919,107.

Specification of Letters Patent.

Patented April 20, 1908.

Application filed June 19, 1905, Serial No. 266,001. Renewed August 5, 1908. Serial No. 447,127.

To all whom it may concern:

Be it known that I, ARTHUR YANCEY, a citizen of the United States, residing at Dermott, in the county of Chicot and State of Arkansas, have invented certain new and useful Improvements in Seining Apparatus; and I do hereby declare the following to be a full, clear, and exact description of the invention, such as will enable others skilled in the art to which it appertains to make and use the same.

This invention relates to improvements in seining apparatus.

In former applications, I have illustrated and claimed the broad idea of providing a support at the surface of the water with a depending arm carrying means for bringing together the lead lines of a seine while being hauled and landed, also broadly and specifically such closing means associated with power actuated mechanism for hauling and landing the seine while being closed.

In the present application the object of the invention is to provide a suitable support carrying mechanism constructed and operating to mechanically haul a seine and to land and bunt the web thereof while being hauled, and in this connection it might be said that the term "bunting" is commonly used by fishermen to refer to the setting of the seine for re-casting without intervening adjustment after it has been hauled and landed.

Other objects and advantages will appear from the following description, and the particular features of novelty will be pointed out in the claims, and while the invention is not restricted to the specific details illustrated and described, for the purposes of disclosure reference is had to the accompanying drawings, showing a practical embodiment of the invention, and while the construction illustrated is preferable in many respects, I am aware that other forms of the apparatus than that illustrated can also be employed for accomplishing the "bunting" of the seine. For instance one or more floats may be employed provided with the form of hauling winch shown in my application, No. 243,089, filed January 28, 1905, and the seine simply piled on deck as it is hauled and landed.

In illustrating the invention, however, I have shown a support comprising detachably connected floats or boats, each float carrying mechanism capable of operating in reversed

directions of movement, so that when the floats are connected and the seine set, said mechanism may be operated to haul and symmetrically land or bunt the webs of the seine, and when the floats are detached they may be propelled in different directions and the hauled seine re-cast by the reverse direction of movement of the hauling mechanism.

Referring to the accompanying drawings:—Figure 1 is a perspective view of my improvements with the seine in its set position and parts being broken away for clearness of illustration, and Fig. 2 is a fragmentary detail view of a modified means for connecting the hauling mechanism with the driving power.

1 and 2 are complementary detachable members forming a floating support, preferably in the form of self-propelled boats and each of which is preferably provided with similar mechanism, except as herein-after referred to. Each of the boats is provided with mechanism operative in reversed directions of movement and adapted in one direction of movement to symmetrically land the web of a seine and in the reverse direction of movement to pay out said web. In the drawings, this mechanism is illustrated as comprising a seine reel 3 rotatably journaled on suitable supports 4 and one of the flanged heads of the reel being preferably grooved to receive an operating cable. Adjacent the seine spool and extending longitudinally thereof is an elongated guiding roller 5. This roller may be journaled in any suitable way, but in the drawings for the purpose of illustration I have simply shown supports provided with inwardly directed pintles 6 disposed within recesses 7 formed in the end of the roller.

8 designates a frame of gang-way construction, pivotally suspended as by the cross arm 8^a, to one of the boats adjacent its guiding roller. One of the depending arms 9 of this frame cooperates with a parallel arm 9^a, also connected with the cross arm 8^a, to pivotally suspend a sled block hereinafter referred to. At opposite ends of the arms 9 and 9^a are secured the auxiliary arms 10—10^a to form another frame, referred to as the barrier frame, adapted to have a netting 11 carried thereby and extending longitudinally to the rear of the space between the arms 9 and 9^a from substantially the bottom of the frame to the surface of the water.

2 Suitable closing mechanism is employed for bringing together the lead lines of the seine while being hauled, and in the drawings I have illustrated a sled block 12 pivotally suspended as shown by the lower ends of the arms 9-9^a. Suitably journaled on the sled block may be arranged four rollers journaled on axes laterally of said sled block so as to form sets of rollers 10 with one roller of each set disposed above the other roller of its set when the sled block is disposed in operative position.

15 In the drawings, 13 designates the lower pair of rollers and 14 the upper pair of rollers journaled in the vertically movable member 15 hinged as at 16 to the sled block, any suitable locking means being provided for holding said hinge member interlocked to said sled block.

20 17 designates a cable at one end connected to the sled block and reeving through a pulley 18 on a boom 19 carried by the mast 20 supported on one of the boats, the object being to elevate the closing means from the bed 25 of the water.

21 designates any suitable means for detachably securing the boats against movement relatively to each other.

22 designates the engines and 23 the propeller shafts of the boats, the latter carrying winding drums 24 freely revoluble on the propeller shaft and adapted to interlock therewith through the medium of the clutch mechanism 24^a.

25 25 designates a suitably supported pulley for taking up the slack of the operating cable, and 26 are idler pulleys disposed to guide the operating cables 27 in alinement with the grooved heads of the seine reel 3. It is ob-

40 vious, however, that any other suitable means may be provided for driving the seine rollers 3; for instance I may employ the construction illustrated in Fig. 2 wherein 28 designates a bevel gear wheel on the propeller shaft 23, said gear wheel being so keyed as to be free to move longitudinally thereof but locked against independent rotary movement, and said bevel gear 28 being operative longitudinally of the propeller 45 shaft by a suitable lever mechanism 29. Associated with the gear wheel 28 is a bevel gear wheel 30 disposed at right angles to said first gear wheel and mounted on the stud shaft 31 carrying at its other end a cable 50 drum 32 disposed in alinement with the grooved head of the seine reels 3 and adapted to have the cable 27 passed therearound, the slack of the cable being taken up by a suitably located slack pulley 25.

55 60 A and A' designate the webs of the seine, B the cork lines thereof, and C the lead lines.

It will be seen in operation that the seine being set in the position shown in the drawings with the boats secured together, upon 65 starting the engines and throwing in either

or both of the clutches (dependent upon whether one or both webs of the seine are to be hauled), the cable 27 will rotate the seine reels inwardly and wind up thereon the web of the seine, one web of the seine being wound on the seine reel carried by the boat 1 and the other web being wound up on the seine reel carried by the other boat or floating member 2, and the cork lines being disposed at the outer end of the seine reel with the lead lines at the inner end. At the same time, while the webs of the seine are being wound up, the closing means carried by the sled block 12 bring together the lead lines of the seine and lead them upwardly to the surface of the water in front of the barrier netting 11, the barrier netting being adapted to close the space between the arms 9, 9^a and thus prevent the escape of the fish through this opening. Contrariwise when the boats 80 are detached and the cable drums thrown out of gear with the propeller shafts, it is apparent that the boats may be headed in any direction and their forward propulsion will allow the webs of the seine to be rapidly 85 paid out. Thus it is obvious that the wings of the seine may be first set in any desired direction and after being paid out for instance by steering the boats in opposite directions of substantially the same circle, a great area may be covered by the time that 90 the boats are brought together and the seine re-set for hauling.

Having thus described the invention what I claim is:

1. In seining apparatus, the combination of a support and means operative in one direction to haul and land the wings of a seine and in a reverse direction of movement to re-cast same.

2. In seining apparatus, the combination with a support, of a revoluble member carried thereby and co-operating with a seine to haul and wind thereon the web of said seine, whereby the web of said seine is mechanically 110 adjusted for re-casting.

3. In seining apparatus, the combination with a support composed of a pair of detachable floating members, of mechanism carried by one of said floating members for 115 hauling in and landing the web of a seine said detachable floating members upon propulsion co-operating with said hauling mechanism to assist in paying out the web of said seine for re-casting.

4. In seining apparatus, the combination with a support, of a pair of coacting reels adjacently mounted on said support and adapted to receive and wind up thereon the web of a seine, and means for operating said reels.

5. In seining apparatus, the combination with a support, of a pair of revolvably mounted co-acting reels adjacently mounted on said support and adapted to receive and wind up thereon the web of a seine in one

direction of rotation and to pay out the web of the seine in the reverse direction of rotation, and means for operating said reels.

6. In seining apparatus, the combination 5 with a support composed of detachable floating members, of mechanism carried by said floating members for hauling in and landing the wings of a seine, said detachable floating members upon propulsion coöperating with 10 said hauling mechanism to assist in paying out the wings of said seine for re-casting.

7. In seining apparatus, the combination 15 with a support composed of a pair of floating members and securing means therefor, of a seine reel mounted on each of said members and adapted to receive and wind up thereon a wing of a seine, closing means coöperating with the lead lines of the seine, and means coöperating to rotate said reels in one direction of rotation and release them to freely 20 rotate in the opposite direction.

8. In seining apparatus, the combination 25 with a support composed of a pair of floating members and means for securing the same against independent movement, a seine reel independently mounted on each of said members, adapted to receive and wind up thereon a wing of a seine, closing means depending from one of said members, adapted to engage 30 the lead lines of the seine, and means coöperating to rotate said reels in one direction of rotation and release them to freely rotate in the opposite direction.

9. In seining apparatus, the combination 35 with a support, of a pair of seine reels mounted thereon and adapted to receive the wings of the seine, elongated guiding rollers longitudinally disposed adjacent said seine reels, and means for operating said reels.

40 10. In seining apparatus, the combination 40 with a support comprising a pair of detachably connected floating members, of means carried by said members for symmetrically landing the wings of a seine, means for bringing together the lead lines of the seine for 45 closing the wings thereof while being landed,

and means for closing the space, between the lead lines, extending from the water bed to the aforesaid support.

11. In seining apparatus, the combination 50 with a support, comprising a pair of detachably connected floating members, of means carried by said members for symmetrically landing the wings of a seine, closing means for the wings of the seine suspended from one 55 of said floating members and projecting substantially between said members, and a barrier extending from said closing means to said support adjacent the path of travel of the lead lines of the seine.

60 12. In seining apparatus, the combination with a floating support and means for hauling and symmetrically landing the wings of a seine thereon, of pivoted depending means of gang-way construction, carried by said support, and closing mechanism secured to the lower end of said depending means for bringing together the lead lines of the seine while being hauled.

65 13. In seining apparatus, means for leading together the lead lines of a seine for closing the wings thereof while being hauled, comprising a plurality of pairs of horizontal closing rollers and one roller of each pair being disposed above the other roller of the 70 pair when arranged in operative position.

14. In seining apparatus, the combination 75 with a support and means for hauling and landing a seine thereon, of means associated with said support for bringing together the lead lines of the seine for closing the wings thereof while being hauled, comprising a plurality of pairs of closing rollers rotating on horizontal axes and one roller of each pair being disposed above the other roller of the 80 pair when arranged in operative position.

In testimony whereof, I affix my signature in presence of two witnesses.

ARTHUR YANCEY.
